United States Patent Office

Des. 189,081
Patented Oct. 18, 1960

189,081

FAUCET

Jon W. Hauser, St. Charles, Ill., assignor to Elkay Manufacturing Company, Chicago, Ill., a corporation of Illinois

Filed Nov. 6, 1959, Ser. No. 58,239

Term of patent 14 years

(Cl. D91—3)

FIG. 1

I claim:

The ornamental design for a faucet, substantially as shown and described.
